CUBE SUGAR DISPENSER

John G. Myers and John D. Arrowsmith,
Seattle, Wash.Application September 19, 1931
Serial No. 563,712

4 Claims. (Cl. 312—94)

Our invention relates to dispensing apparatus for the delivery of cubes of sugar, such devices being intended particularly for restaurant use, whereby a patron may deliver from a container 5 as many single cubes as he may desire without the necessity of handling the cubes at all, and indeed without the likelihood that the cubes will be handled by any person, since they may be dumped from the boxes in which they are sold 10 into the receptacle.

It is an object of our invention to devise a machine of the general character indicated, into the receptacle of which a large number of cubes of sugar may be deposited without any necessity 15 for placing them in order, and which has means to segregate individual cubes in pockets of a step-by-step rotatable wheel, straightening out such cubes as may not lie flat upon the bottom of the pockets, or which may tend to project one 20 corner above the level of the wheel, which will separate all other cubes from the cubes thus received in the pockets, and which will deliver these individual cubes from the pockets to a discharge chute, the whole action being automatic 25 as the wheel is advanced to deliver the cubes.

It is more especially an object of our invention to provide mechanism having the advantages indicated above, wherein the devices for handling, pocketing, and straightening out the 30 cubes, and the devices insuring their delivery in proper order to the pockets, will take but a small portion of the space within the receptacle, to the end that the volume within the receptacle may be largely devoted to holding the cubes, and its 35 capacity may be as great as possible.

Other objects, and more especially those pertaining to mechanical details of the invention, will be understood from a study of the present specification, the drawings accompanying the 40 same, and the claims.

Our invention comprises the novel parts, and the novel combination and arrangement thereof as shown in the accompanying drawings, described in the specification, and more particularly defined in the claims terminating the same.

In the accompanying drawings we have shown our invention, insofar as is concerned the sugar handling mechanism, in a preferred form, and insofar as the feed mechanism is concerned, that 50 shown is illustrative of a form which may be found suitable. The specific form of the feed means has no essential relationship with the specific form of the sugar handling devices.

Figure 1 is an elevation of the machine in position for use.

Figure 2 is a vertical axial section through the container and associated devices, taken at right angles to Figure 1.

Figure 3 is a plan view of the receptacle, the cover being omitted.

Figure 4 is a transverse section through the bottom of the receptacle showing the feed mechanism.

Figure 5 is a vertical section through the receptacle showing the shield in edge view.

Figure 6 is a section substantially on the line 6—6 of Figure 5.

Essentially the device comprises a receptacle 1, preferably cylindrical in shape, or at least cylindrical in its bottom portion, a wheel 2 resting upon the bottom 10 of the receptacle and having pockets 20 therein, preferably formed in its periphery, a shield 3 to separate all other cubes from one which has been received in a pocket moving into registry with a discharge chute 11, 75 by means of which cubes are discharged from the receptacle, and mechanism for advancing the wheel 2 step by step, such means terminating in a convenient operating member, such as the button 4 placed conveniently to be pressed by the 80 thumb of the user's hand, the fingers of which grasp the handle 12 which supports the receptacle. The receptacle ordinarily would have a cover 13, which might be of glass, so that the 85 patron may see whether or not there is sugar in the receptacle.

The wheel 2 may be made in various ways, and it may conveniently be formed of a sheet of metal, peripherally slit and then transversely slit at the base of the peripheral slits, to form 90 flaps 21, which are bent downwardly to form the sides of the pockets 20. The inner sides of the pockets may be left open, or they may be completed, partially at least, by a downwardly turned flange 22 secured to and projecting 95 downwardly from the wheel 2 to a point adjacent the bottom 10 of the receptacle, whereby the upper surface of the wheel 2 is spaced above the bottom 10 by an amount slightly in excess of the height of a sugar cube. The wheel is suitably supported for rotation, as for example, upon a vertical shaft 5 journaled in the bottom 10, and beneath this bottom connected to the feed mechanism to be described hereafter.

It is necessary that some means be provided 105 to direct individual cubes, as nearly as possible in proper position, to enter the pockets 20, yet such means must not take up any large part of the space within the receptacle. As a convenient means of accomplishing these two ends, 110

then,—directing the cubes and positioning them in advance of their entering the pockets—we provide a flat cone 23 which is mounted upon the central portion of the wheel 2, its base lying at the level of the wheel and its periphery lying substantially at the inner edge of the several pockets. Thus, as may be seen in Figure 2, the cubes will arrange themselves substantially flat upon this cone, as they reach the bottom of the receptacle, nearly in the position they will occupy when in the pockets, and then will tend to slide outwardly in this nearly flat position, until, when they reach a pocket which is empty, they will drop over into this pocket, and will tend to lie flat therein.

It is of course essential that some means be provided to separate the one cube C (Figure 2), which is to be discharged, from all the other cubes, and the shield 3 accomplishes this end. However, this shield, overlying that pocket which is in registry with the discharge chute 11 and the aperture 15 in the bottom 10 which admits thereto, may perform a further function; it will throw back toward the center and upon the cone 23 all other cubes, and in a sense will cause relative movement between the several cubes within the receptacle, to break up any tendency to jam and stick in a mass, and to clear away cubes which have not yet entered a pocket, so that the pockets will be filled by cubes sliding off the cone, these latter cubes being positioned by the cone in such a way that there is the least likelihood of their sticking. To this end the shield 3 is curved upwardly and outwardly, so that any cube, such as C' in Figure 6, which rests upon another cube in a pocket, is separated therefrom by the leading edge of the shield 3, and then is caused to ride up on the curved shield 3 until it is tumbled over and pressed inwardly, tending again to fall upon the cone 23 or upon cubes resting thereon, to be directed by this cone into an empty pocket.

Occasionally cubes will be deposited in the pocket resting upon an edge, as indicated at C' in Figures 3 and 6. Cubes so positioned will not pass under the shield 3, and in order to insure that they are properly positioned, and yet to prevent jamming of the feed mechanism, we provide a prong 31 which projects in advance of the leading edge of the shield 3, in the direction from which the sugar cubes advance, and which will engage the projecting portion of a cube, penetrating it slightly, and fixing this projecting portion so that the pressure of the wheel as it is advanced tends to rotate the cube C' about the point of this prong 31, thereby causing it to straighten out and eventually to drop back into the pocket, so that it may pass beneath the shield 3. This action is automatic and requires no time or particular effort, and we have found that the employment of such a prong materially prevents the formation of jams which would prevent feeding of the sugar, and which, if there were no means to straighten them out, would require the emptying of the receptacle to get at the sticking cube at the bottom thereof, which would render the dispenser as a whole impractical.

The feeding mechanism, as has been mentioned, may be any which is found suitable. As herein shown, a ratchet wheel 40 is mounted upon the lower end of the shaft 5. Its edge is notched, as indicated at 41, and these notches serve as the teeth with which may be engaged the spring dog 42 upon a lever 43. This lever

is journaled upon the shaft 5, being held toward the wheel 40 by means of a spring 44, and it is operated by means of a link 45, one end of which is connected to the lever 43 and the other end of which is connected to a crank arm 46. The opposite end 47 of this crank arm is connected to a rod 48 connected to the button 4. The rod 48 is guided for vertical movement in a recess 19 in the handle 12. A spring 49 secured to the bottom 10 engages the notches 41 and serves as a holding pawl. A spring 51 serves to return the dog 42, following its advance under the pressure of the button 4, into position ready to advance the wheel 40 again. In Figure 4 parts are shown in position following an advance, but before return to normal position.

What we claim as our invention is:

1. A cube sugar dispenser comprising a cylindrical receptacle having a discharge chute, a pocketed member upon the bottom of said receptacle of a height substantially equal to that of a sugar cube and adapted to receive individual cubes in such pocket, means to advance said member by an amount to bring a pocket into registry with the discharge chute, and a shield secured to the receptacle having its forward edge, with relation to the advance of said member, disposed immediately above the member, at one side of the receptacle and in advance of the position of a pocket when the latter registers with the discharge chute, and said shield being curved upwardly and rearwardly from its forward edge in a smooth curve, to direct sugar cubes sliding thereover upwardly through the mass of cubes, to fall towards the center of the receptacle.

2. A cube sugar dispenser comprising a cylindrical receptacle having a discharge chute, a wheel upon the bottom of said receptacle of a height substantially equal to that of a sugar cube and having pockets for the reception of individual cubes, means to advance said wheel by an amount to bring each pocket in turn into registry with the discharge chute, and a shield secured to and at one side of the receptacle, having its forward edge, with relation to the advance of said wheel, disposed immediately above the wheel and in advance of the position of a pocket when the latter registers with the discharge chute, the forward portion of said shield being substantially in the plane of rotation of the upper surface of the wheel, and the shield's upper surface curving continuously upwardly and rearwardly from such forward portion.

3. A cube sugar dispenser comprising a cylindrical receptacle having a discharge chute, a wheel upon the bottom of said receptacle of a height substantially equal to that of a sugar cube and having pockets for the reception of individual cubes, means to rotate said wheel step by step to bring each pocket into registry with the discharge chute, an upwardly curved shield disposed immediately above the wheel pockets, at one side of the receptacle and above the discharge chute, to separate all other cubes from that in the pocket moving into discharge position, and a prong projecting in advance of said shield, in the direction of feed of the wheel, to engage and depress into its pocket an advancing cube which is cocked above the upper level of the wheel.

4. A cube sugar dispenser comprising a cylindrical receptacle having a discharge chute, a wheel upon the bottom of said receptacle of a

height substantially equal to that of a sugar cube and having pockets for the reception of individual cubes, means to rotate said wheel step by step to bring each pocket into registry with the discharge chute, a flat cone raised above the wheel, its base lying in the level of the upper surface of the wheel, whereby cubes resting thereupon are directed outwardly by gravity, and a shield disposed immediately above the level of the pockets, at one side of the receptacle, and above the discharge chute, its leading

portion, in the direction of advance of the wheel, being substantially level with the wheel, and its upper surface curving upwardly and rearwardly to separate all other cubes from that in the pocket which is moving into discharge position, and to direct such other cubes upwardly along the wall of the receptacle and inwardly upon said cone. 30
